LESTER M. LLEWELLYN AND HAROLD G. PEDERSON, OF SYRACUSE, NEW YORK; SAID
LLEWELLYN ASSIGNOR TO SAID PEDERSON.

COUNTERBALANCING DEVICE.

Application filed October 23, 1923. Serial No. 670,349.

This invention has for its object a counterbalancing device for articles, such as motor actuated tools, which are suspended from overhead and when used are pulled down by the operator against counter-balancing means to a desired height and swung horizontally to any desired position, such as for instance, motor driven screw and nut driving machines, grinders, etc., in which the electric or air motor is carried by or is a unit with the tool. Which device is particularly simple in construction and highly efficient and durable in use, by which the tool stops in any position without overthrowing or oscillating movements due to momentum given it.

Figure 1 is a side elevation of this counter-balancing device.

Figure 2 is an elevation partly in section, looking to the right in Figure 1.

Figure 3 is a fragmentary detail view of a modified form of reel.

Tools which are driven by electric or air motors, such as, tools used to drive nuts and screws in assembling machines, or for operating grinders, etc., which tools are shiftable at will by the operator to reach the work to be performed, are suspended and counterbalanced, so that, when the workman desires to discontinue the use of the tool, he pushes it upwardly above his head. Counterbalancing means have usually embodied weights or springs. The weights oftentimes when coming down or when the tool is being swung, strike other workmen or if a spring is used the spring overthrows and carries the tool up either with a jerk or too high.

Our invention comprises a counterbalancing means, by which the tool can be accurately counterbalanced and moved up and down without the use of weights and without undue overthrow and working up and down. My invention comprises generally a case, a reel mounted in the case, a cable winding on the reel and supporting the tool or other article, and means for suspending the casing and the tool attached thereto, so that, the case has a freedom of movement which permits the cable to be pulled out and wound up without undue rocking and swing horizontally of the casing and the tool.

1 designates the casing, which is here shown as a drum or barrel open at one side,

2 is a cover plate for the open side, the cover plate being secured thereto in any suitable manner, as by screws 3. 4 is the reel mounted on a shaft 5, which is supported in the drum 1 and the cover 2, the reel having a hub 6 rotatable about the shaft 5, 7 is a part or bearing member in the form of a sleeve provided on the cover plate 2 and rotatably adjustable about its axis in an opening in the same, this sleeve having a portion 8 surrounding the hub 6 of the reel.

9 is the coiled flat-spiral spring, located in a recess in the reel and fixed at its outer end to the reel and at its other end to the sleeve 7 or the portion 8 thereof.

10 is a cable extending through an outlet passage 11 in the casing and winding on the reel or in a peripheral groove 12 in the reel 4. This cable supports the tool. The spring is tensioned sufficiently to hold the cable with the tool thereon at any level to which the tool is placed and the spring can be adjusted to the weight of the tool by removing the screws 13 which hold the sleeve 7 in position and turning the hub in one direction or the other and replacing the screw.

The outlet passage 11 extends downwardly from one side of the lower part of the case and is arranged substantially tangent to the reel.

In Figure 3 the reel 4^a is shown as formed with an additional groove 14, in which winds the electric cable supplying current to the electric motor of the tool when the tool is electrically operated.

A spring pressed latch 40 carried by the casing, coacts with the reel to hold the reel in its starting position and also to prevent winding up of the wheel violently when no load is attached to the end of the cable 10, the reel being provided with a hole 41 in which the tapered end of the latch enters. The latch is here shown as a poppet pressed into operative position by a spring 42.

The casing is suspended so as not to rock unduly when the tool is being raised or lowered, by means connected to the upper side of the casing on the same side thereof that the tangential outlet 11 is located, this means being connected to the casing, so that, the weight of the case and parts carried thereby is applied to the suspension means in a vertical line parallel to the cable 10 between

the axis of the reel and the point where the cable 10 leaves the reel and nearly in line with the vertical portion of the cable 10. This means is here shown as a link 15 connected at 16 to the upper side of the casing or the upper quarter of the casing directly above the quarter from which the tangential outlet 11 extends. By reason of the arrangement of the suspension means relatively to the cable 10 and the outlet 11, the casing 1 remains stationary except for swinging about a vertical axis and does not rock appreciably about any horizontal axis and hence, the spring being properly tensioned the tool will stay at any level to which it is placed and will not overthrow and also will not oscillate up and down.

What we claim is:

A counter-balancing device comprising a casing, a reel mounted in the casing, the casing having a downwardly extending outlet on the lower side thereof, substantially

tangent to the reel, a part carried by the casing and extending axially into the reel, a spiral spring secured at one end to the reel and at its other end to said part, a cable for supporting an article on the reel and extending through the tangential outlet, and a link adapted to receive suspending means at its upper end and pivotally secured at its lower end to the casing above the tangential outlet at a point between the axis of the reel and the axis of the tangential outlet, and providing a flexible connection for the casing and permitting a floating action of the device as a unit on the said pivot below the link suspending means.

In testimony whereof, we have hereunto signed our names, at Syracuse, in the County of Onondaga, and State of New York, this 2nd day of October, 1923.

LESTER M. LLEWELLYN.
HAROLD G. PEDERSON.
